UNITED STATES PATENT OFFICE

WILLIAM A. BULL, OF LOS ANGELES, AND VERNON R. MACKIE, OF SOUTH PASADENA,
CALIFORNIA

CONCRETE-FORM-BINDING TOOL

Application filed December 9, 1927. Serial No. 238,985.

Our invention pertains to wire and strap iron snubbing brackets for binding concrete structural forms in rigid position, and has for its objects, among others, to provide a tool 5 which can be easily and quickly placed by one man; that does not mar the lumber; by which the binding wire or strap may be tightened to any necessary degree and that may be locked in taut position instantly; that is simple in operation, durable, economical of employee's time, and cheap to manufacture.

These objects we attain by the provision, formation and assemblage of the members and parts illustrated in the accompanying 15 drawings, in which

Figure 1 is a side elevation of the complete tool.

Figure 2 shows application of the tool in two positions on the form work of a concrete 20 wall.

Figure 3 is a cross section of the operating bracket and lever handle in closed position (A), and open position (B), and the gripping members therein.

25 Referring more particularly to the drawings:

1 indicates the operating bracket of the tool, and 2 indicates a companion bracket for the fixed end of the wire or strap.

30 3 indicates a hollow lever handle, pivoted within rearwardly projecting flanges of bracket 1, on pivot 5.

4 indicates a rectangular transverse block riveted to handle 3 to provide an integral 35 part thereof.

6 indicates a rectangular transversely positioned block eccentrically revoluble on pivot 5 and adapted to co-act with block 4 in gripping action.

40 7 indicates a wire or strap adapted to hold outside and inside wales of a concrete form in rigid position to prevent spreading.

8 indicates transverse slots stamped in the rear face of bracket 2, adapted to allow a 45 metal strap to pass therethrough for snubbing purposes, the metal between said slots being stamped to form a groove exterior to the body of the bracket adapted to receive wire 7 therethrough for snubbing purposes.

50 9 indicates a resilient tongue formed cres-

centically to project inwardly from the surface of any side face of the brackets, adapted to hold the bracket in position on the wale while the other bracket and binding wire or strap are being positioned.

12 indicates upright studs placed at intervals against board forms 13.

14—14 indicate wales placed horizontally at intervals and upon which brackets 1 and 2 are mounted.

55 Slight depressions are provided at approximate the center of coacting surfaces of blocks 4 and 6 (not shown) to afford safer gripping for wire, and to avoid shearing the same.

60 The brackets herein described are intended to be placed at intervals of approximately 24 inches on the horizontal wales, and to avoid side pull or twisting effects thereby it is best to stagger them, i. e. that the binding wire or strap be placed above and below the wale alternately. The position of the lever handle in closed position, up or down, is shown in Figure 2.

65 The procedure in proper use of this tool is to apply the binding wire or strap (as the case may be) and snub one end in bracket 2, through groove or slots 8; place bracket 2 on a wale where tongue 9 will hold it in place while the other end of strap 7 is passed

70 through the form to bracket 1 which has been positioned on the corresponding wale. The loose end of strap 7 is passed between gripping members 4 and 6 while lever 3 is in open position. While traction is made by

75 one hand on the exposed end of strap 7, lever handle 3 is moved from open to closed position, this movement serving to automatically grip strap 7. As the movement progresses the slack or strap 7 is taken up to

80 a maximum of the diameter of the circle described by the contact points of members 4 and 6.

85 Any degree of tension on the strap less than the maximum is readily controlled by the amount of hand traction when the movement of handle 3 is begun.

90 Reversal of the above outlined process will serve to release the traction on strap 7 and the brackets may be removed, although it is

more expeditious to cut the strap at convenient points and then clear the brackets.

It will be apparent that various changes and modifications may be resorted to without departing from the spirit and scope of our invention, and we do not wish to limit ourselves to the exact disclosures herein.

Having thus disclosed our invention and its mode of operation, we claim as new and 10 seek Letters Patent of the United States upon:

1. A concrete form-binding tool of the character disclosed, comprising two rectangular U shaped brackets adapted to span the edge 15 of a wale; one of said brackets provided with transverse slots adapted to allow snubbing of a wire or strap therein; resilient means of maintaining said brackets upon a wale comprising a tongue inwardly projecting from the face of said brackets; the other bracket provided with a lever arm pivoted in outwardly projecting flanges thereon; means for gripping a binding wire or strap within said handle comprising a flat 20 surface integral with said arm, and a rectangular eccentrically mounted transverse member adapted to contact with said integral flat surface in gripping action, said gripping means being positioned relative to said lever 25 arm pivot to tighten and snub said wire or strap while said lever arm moves from open to closed position; and means for locking said lever arm in closed position.

2. A concrete form-binding tool of the 30 character disclosed comprising brackets adapted to span the edge of a wale, one of said brackets being provided with transverse slots adapted to allow snubbing of a wire or strap therein; the other bracket being provided with a lever arm pivoted in outwardly 35 projecting flanges thereon; means for gripping and binding a wire or strap within said handle, comprising a flat surface integral with said arm, and an eccentrically mounted transverse member adapted to contact with 40 said integral flat surface in gripping action, said gripping means being positioned relative to said lever arm both to tighten and snub said wire or strap while said lever arm 45 moves from an open to a closed position.

3. A concrete form-binding tool of the character disclosed comprising brackets adapted to span the edge of a wale, one of said brackets being provided with transverse 55 slots adapted to allow snubbing of a wire or strap therein; the other bracket being provided with a lever arm pivoted in outwardly projecting flanges thereon; means for gripping and binding a wire or strap within said 60 handle, comprising a flat surface integral with said arm, an eccentrically mounted transverse member adapted to contact with said integral flat surface in gripping action, said gripping means being positioned relative to 65 said lever arm both to tighten and snub

said wire or strap while said lever arm moves from an open to a closed position, and means for locking said lever arm in closed position.

In testimony whereof, we have signed our names to this specification at Los Angeles, Calif., this 28th day of July 1928.

WILLIAM A. EULL.
VERNON R. MACKIE.
